FISHHOOK FORMING DEVICE

Walter S. Peterson, Sr., Denver, Colo.

Application April 6, 1946, Serial No. 660,182

10 Claims. (Cl. 29—9)

1

This invention relates to the manufacture of fishhooks, and has as an object to provide improved means power-actuatable to work, shape, and condition wire stock into barbed fishhook form.

A further object of the invention is to provide improved powered means actuatable to automatically and progressively convert wire stock into barbed fishhook form.

A further object of the invention is to provide improved fishhook-forming means of multi-station type arranged for gravity transfer of stock material between successive stations.

A further object of the invention is to provide improved fishhook-forming means having multiple stations whereof the operating elements synchronously respond to the power reciprocation of a single actuating member.

A further object of the invention is to provide improved fishhook-forming means having multiple stations spaced for successive, synchronous operation along a feedway longitudinally accommodating the work stock.

A further object of the invention is to provide improved fishhook-forming means arranged for simultaneous, single-member actuation of paired mechanisms operatively associated with parallel, independent stock feedways.

A further object of the invention is to provide improved fishhook-forming means adapted for the simultaneous production of different size fishhooks in response to cyclic reciprocation of a single actuating member.

A further object of the invention is to provide improved fishhook-forming means susceptible of convenient multiple assembly as a powered unit for the simultaneous production of fishhooks in a variety of sizes.

A further object of the invention is to provide improved fishhook-forming means of multi-station type arranged to simultaneously accomplish a plurality of stock-modifying operations at each station.

A further object of the invention is to provide improved fishhook-forming means that is relatively simple and inexpensive of construction, positive, efficient, and rapid in fully automatic operation, susceptible of ready structural adaptation and multiple combination to meet an almost infinite range of unit size and output quantity requirements, and economical in power and maintenance needs.

With the foregoing and other objects in view, my invention consists in the construction, arrangement, and combination of elements herein-after set forth, pointed out in my claims, and illustrated by the accompanying drawings, in which—

Figure 1 is a front face view of a unit embodying the principles of the invention as arranged

5 2

for practical use with its actuating member at one limit of its operative range. Figure 2 is a view of the structure according to Figure 1 with the actuating member at the other limit of its operative range. Figure 3 is a vertical section taken longitudinally through and substantially on the indicated line 3—3 of Figure 1. Figure 4 is a section similar to Figure 3 taken substantially on the indicated line 4—4 of Figure 2. Figure 5 is a transverse section taken on the indicated line 5—5 of Figure 1. Figure 6 is a fragmentary, detail section, on an enlarged scale, taken substantially on the indicated line 6—6 of Figure 4. Figure 7 is a fragmentary, detail section, on an enlarged scale, taken substantially on the indicated line 7—7 of Figure 2. Figure 8 is a section similar to Figure 7 taken substantially on the indicated line 8—8 of Figure 2.

In the construction of the typical embodiment of the improved device as shown in the drawings, the numeral 15 designates a base plate or table whereon the other elements of the assembly are mounted, grouped, positioned, and operatively associated. The table 15, of any shape or size conveniently suited to its purpose, is of hard, rigid material, such as metal, has a plane, smooth, upper surface, and is adapted to be fixedly supported in use with its upper surface inclined to the horizontal at an angle such as will induce sections or units of stock material to slide freely thereon under the influence of gravity from the upper and to the lower margin thereof. A straight groove, shallow in relation to its width, centrally intersects the table 15 upper surface in traversing relation between the table upper and lower margins to slidably seat and reciprocably accommodate a straight, rigid actuating member 16 of a length somewhat less than that of said groove, and suitable stops 17 and 18 are fixed to the table 15 in obstructing relation across the opposite ends of said groove to positively limit the range of member 16 reciprocatory travel therein. For convenient cooperation with and actuation of elements of the assembly hereinafter to be described, the member 16 is preferably of a thickness greater than the depth of its groove or slideway, so that said member rises from and extends above the major plane of the table 15 upper surface.

Production of fishhooks by means of the improved apparatus is a consequence of continuous, cyclic reciprocation of the member 16 relative to the table 15 in its groove or slideway between the stops 17 and 18; and while the desired member 16 reciprocation may be power-accomplished through various mechanical linkages and arrangements adapted for the transmission of power, a pneumatic or hydraulic, automatically-reversible, power drive for said member of the type shown and hereinafter de-

scribed is particularly effective and desirable. As shown, a bracket member 19 fixedly depends from an upper central portion of the table 15 under side to hingedly connect at its lower end with and support one end of a pneumatic or hydraulic cylinder 20 operatively housing a piston whereof the stem 21 projects through and axially of the unhinged cylinder end in spaced alignment with and below the member 16. Adjacent and beneath the lower end of the member 16, a slot 22, elongated in the direction of said member reciprocation, opens through the table 15 and floor of said member groove or feedway in registration with a relatively shorter aperture 23 intersecting said member lower end, and lugs 24 fixedly depend from the table 15 under surface on opposite sides of said slot 22 to support a transverse hinge member 25 whereon a lever 26 is mounted for oscillation in a vertical plane longitudinally intersecting the member 16. The upper end of the lever 26 is formed with a transversely-cylindrical head 27 engaging within and to operatively bear against upper and lower margins of the aperture 23, and the lower end of said lever is hingedly connected with the free end of the piston stem 21 so that, the effective lengths and operative dispositions of the pertinent elements being properly proportioned, extension and retraction of the stem 21 relative to its cylinder 20 is reflected as proportional, oppositely-directed reciprocation of the member 16 relative to the table 15. Automatically-controlled, cyclic, power actuation of the piston and cylinder unit is conveniently had through the agency of a reversible pressure flow control valve assembly 28 fixed to the table 15 under side beneath the upper end of the member 16 with its shiftable, flow-reversing element operatively linked, as at 29, to a lug 30 fixedly depending from the member 16 upper end through a slot in the table 15 disposed for operative accommodation thereof. The valve assembly 28 is served by a pressure flow line 31, leading from any convenient source or supply of fluid under pressure, and pressure flow lines 32 connect the alternative pressure flow outlets of said assembly 28 with the opposite ends of the cylinder 20, the operative arrangements and adjustments of the pressure responsive and control elements being such as to reverse pressure flow to the cylinder 20 at each limit of member 16 reciprocation and thereby maintain cyclic power actuation of said member as long as fluid flow at adequate pressure is available through the line 31.

The member 16 cooperates with and actuates a plurality of stations operatively disposed along and to define a feedway for stock material spacedly paralleling each side of said member, the feedways and associated stations on the opposite sides of said member being functionally identical and structurally similar with only such differences of element form, disposition, and relative spacing as are requisite to adapt the operating line of a given feedway to the formation of a particular hook size from suitably-proportioned stock material; detailed description of but one of said lines hence being adequate for an understanding of both.

The stock material from which the hooks are formed is readily-workable annealed or "soft" metal wire of selected gauge suited to the type and size of hook to be made, which wire is commonly supplied in coils, on spools or reels, or in bundled straight lengths. Regardless of the particular form in which supplied and without

concern as to the specific means and agencies employed for the purpose, wire stock material 33 is fed in continuing supply downwardly across the upper margin of the table 15, against the upper inclined plane face of said table in spaced parallelism with the member 16, and into the upper end of the straight feedway defined by the progressively-arranged stations on the corresponding side of said member. At the upper end of each feedway, the wire 33 traverses and feeds through a pair of functionally-similar, successively-arranged, complementary stations reactive to member 16 reciprocation with straightening effect on the wire portions engaged thereby, the first of said stations comprising a rigid arm 34 hinged intermediate its ends to a bracket 35 upstanding from the table 15 face between the feedway and member 16 upper end and thus disposed for oscillation in a plane perpendicular to the table face and to the member 16 travel path with its inner end overhanging the member 16 upper end and its outer end overhanging the feedway, and a shoe 36 elongated in a direction perpendicular to the arm 34 hingedly depends from said arm outer end with its under surface in spaced, parallel opposition to the table 15 surface constituting the upper feedway portion. The arm 34 inner end is resiliently urged and held toward the adjacent member 16 upper surface, as by means of a retractile coil spring 37 engaging between said arm inner portion and an underlying point on the table 15, to maintain the under margin of said arm inner end in sliding engagement with and against the upwardly-directed cam face of a block 38 fixed to and upstanding from the upper end of said member, and the cam face of said block is so contoured as to elevate said arm inner end and approach the shoe 36 under surface toward the cooperating table 15 surface, with straightening effect in one direction on the wire 33 engaged therebetween, when the member 16 is at the upper limit of its range of reciprocation, and to permit depression of said arm inner end toward the member 16 through the agency of the spring 37, with consequent increase of the spacing between the shoe 36 and table surface, when said member is at the lower limit of its reciprocation. The second of the wire-straightening stations is immediately below and in alignment with the station just described and is arranged for straightening effect on the wire in a direction perpendicular to that of the first station, wherefore said second station conveniently consists of an elongated abutment 39 fixedly upstanding from the table 15 on the outer side of the feedway and defining one side of the latter by means of its straight, long inner face paralleling the member 16, a shoe 40 reciprocable transversely of the table 15 between said member 16 and abutment 39 for coaction at times with the latter, a guide-block 41 fixed to the table 15 between the shoe 40 and member 16, and an actuating finger 42 slidably received through said block 41 in perpendicularly-fixed relation with the shoe 40 to slidably engage at its inner end against the adjacent side margin of the member 16. Suitable resiliently-yieldable means, such as the slot, pin, and spring arrangement shown in Figure 6, act on the finger 42 to urge said finger, with its associated shoe 40, away from the abutment 39 and toward the member 16, thus maintaining the preferably-rounded finger inner end in slidable engagement against the member 16 adjacent side margin and for extension at times

away from the block 41 into seated reception within a cam notch 43 inwardly intersecting the said member side margin. The notch 43 is so disposed along the member 16 and so related with the position of the finger 42 as to register with and receive the inner end of the latter, thereby opening the maximum feedway spacing between the abutment 39 and shoe 40, when the member 16 is at the lower limit of its reciprocatory range, as shown in Figure 1, and said notch is so shaped as to shift said finger outwardly through the guide-block 41 and to thereby approach the shoe 40 toward and into minimum spaced relation with the abutment 39 when said member 16 is moved upwardly away from its lowermost position; the shoes 36 and 40 hence simultaneously clamping with straightening effect and in perpendicularly-related directions against successively-adjacent sections of the wire 33 when the member 16 is ranging in the upper reaches of its travel, and retracting out of said clamped adjustment to fully release the wire 33 for travel longitudinally of the feedway when said member is at the direction-reversing lower limit of its oscillatory cycle.

Immediately below the abutment 39 and on the outer side of the feedway, a block 44 is fixed to and upstands from the table 15 surface to removably and replaceably mount and fixedly position a forming element 45 adjacent the path of wire 33 travel, and a guide-block 46 is fixed to said table 15 between the feedway and member 16 in spaced opposition with the block 44 to position and slidably accommodate a forming element 47 reciprocable transversely of the table 15 between the member 16 and element 45 for end coaction at times with the latter. In an arrangement similar to that of the finger 42, the element 47 is spring-urged toward the member 16 for maximum separation of its outer end relative to the element 45 inner end, and the rounded inner end of said element 47 is thus slidably held against the member 16 side margin in position to register with and at times seat within a cam notch 48 intersecting the member 16 margin below the notch 43, the said notch 48 being so correlated with the member 16 length and element 47 location as to register with and receive said element inner end when said member reaches the lower limit of its oscillatory travel. Adjacent ends of the elements 45 and 47 are respectively formed as complementary female and male dies engageable against opposite sides of a wire 33 traversing the feedway therebetween and are so shaped as to define by their coaction a lateral, outwardly-displaced offset 49 in the wire 33 portion thereby engaged, and adjacent corners of said elements 45 and 47 at the upper end of the said offset 49 are formed as complementary inclined shear jaws 50 coactable to sever the wire 33 at the upper crimp angle of the offset for positioning of the latter at and as the upper end of a separate stock section for subsequent forming into a hook-shank-terminating, closed eye and to initially point the leading end of the following section; it being obvious that upward travel of the member 16 from its Figure 1 disposition operates to shift the element 47 toward the element 45 with offset-forming and wire-severing response of the element die and jaw end portions.

Obstructing the feedway where it emerges from between the blocks 44 and 46 downwardly of the table 15, a guide-block 51, formed with a longitudinal channel constituting an aligned continu-

ation of the feedway and of sufficient width to pass the offset 49 of a wire section, is fixed to said table in covering relation with an anvil 52 sunk into the table 15 across the feedway at a distance below the jaws 50 corresponding to the overall stock wire length of the hook to be formed. The upper surface of the anvil 52 is worked and contoured to function as a wire-pointing die in cooperation with the lower end of a plunger 53 reciprocable in a guide-way through the block 51 lower end portion perpendicular to the table 15, for which purpose the anvil 52 upper surface is coplanar at its upper margin with the feedway floor and thence arcuately diverges from the table 15 plane to elevated relation of its lower margin with the feedway floor, while the plunger 53 lower end is eccentrically arched to substantially close at times against the anvil surface elevated lower margin and complete the definition of an arcuate throat divergently opening toward the upper reaches of the feedway. The plunger 53 is formed on or associated for actuation with the outer end of an arm 54 transversely bridging between the block 51 and member 16 in hingedly mounted relation intermediate its ends with a bracket 55 fixed to the table 15, and the inner end of said arm 54 slidably rides over and along the upper contoured face of a cam block 56 suitably located on and fixed to the member 16, spring means of convenient type, such as at 57, being arranged to yieldably hold the arm 54 inner end against the cam surface of the block 56. The block 56 cam surface is so shaped as to react through the arm 54, as the member 16 is reciprocated, for elevation of the plunger 53 lower end away from the anvil 52 a distance sufficient to freely pass a worked wire stock section therebetween and downwardly along the feedway when the member 16 is at the lower limit of its range of travel, to close the plunger 53 lower end in its nearest approach to the anvil 52, with point-forming effect on a stock wire end engaged therebetween, when said member is at the upper limit of its range of travel, and to dispose said plunger 53 lower end upwardly away from the coacting anvil surface a distance less than will pass the stock material, in which relation said plunger and anvil function as a stop to limit stock material travel downwardly along the feedway, during the rest of the member oscillatory cycle. Opening through the upper end portion of the block 51 in alignment with the feedway thereunder, a slideway inclines downwardly of and toward the table 15 to intersect the feedway just above the anvil 52 and plunger 53, and a chisel-type tool 58 is reciprocably mounted in said slideway with its operating end directed toward the stock wire 33 in the feedway at the upper margin of said anvil. It is the function of the tool 58 to cut and shape a barb on the stock wire in properly-spaced relation with the wire end pointed by the anvil 52 and plunger 53, and to that end the tool 58 projects outwardly from the block 51 and is linked to the outer end of a lever 59 disposed to swing in a plane parallel with the table 15 about a fixed pivot perpendicular to said table between the tool 58 and the member 16. The inner end of the lever 59 overhangs the member 16 between the cam block 56 and notch 48 in position to be alternately engaged and oppositely moved by an abutment 50 fixedly upstanding from said member adjacent the cam block 56 and a pin or stud 61 fixedly upstanding from said member adjacent the notch 48 in upwardly-spaced relation with

said abutment, the disposition of the abutment 60 and stud 61 on the member 16 being so adjusted to the lever 59 position and the oscillatory cycle of said member as to actuate said arm for work-effecting engagement of the tool 58 chisel end against the stock material in the feedway when the member 16 is at the upper limit of its cyclic travel and to retract said tool out of such stock engagement and into clearing relation with the feedway when said member is at the lower limit of its reciprocatory range.

The feedway, in a width adequate to accommodate the worked wire section, is continued as a straight, aligned extension for some distance below the block 51 in the form of a shallow trough defined between spaced, parallel guides 62 fixedly upstanding from the table 15 surface, and said trough registers at its lower end with an aligned channel longitudinally of and through a block 63 fixed to the table 15 in covering relation with the feedway and at one side of the member 16. The feedway-defining channel through the block 63 is straight and unobstructed for the major portion of its length and is formed with a shoulder 64 adjacent its lower end outstanding from the channel side wall remote from the member 16 and directed toward said member in position to be engaged by the lower crimp of the offset 49 formed on a stock wire section slidably traversing the feedway, which engagement serves to check the travel of and to position said section relative to forming agencies adapted to act thereon. A slideway through the lower portion of the block 63 perpendicular to the feedway reciprocably accommodates a die element 65 between the shoulder 64 and member 16 and for coaction with said shoulder in the clamping of a stock wire section shank therebetween, corresponding upper corners of said shoulder and die element outer end being arcuately worked to define an upwardly-directed forming recess. The element 65 is resiliently urged, as by means of a spring 66, in a direction to separate its outer end from the shoulder 64 and to maintain its rounded inner end slidably against the adjacent member 16 side margin, and said member side margin is formed with a cam notch 67 disposed to register with and seat the element 65 inner end, and thereby opening the feedway between the shoulder 64 and element outer end for free passage of a stock wire section downwardly past said shoulder, when said member 16 is at the lower limit of its reciprocation. A laterally-offset forming tool 68 is slidably accommodated in the block 63 for longitudinal reciprocation, in a jogged path generally parallel to the feedway, between feedway-obstructing disposition of its lower end in opposition to the recess formed by the shoulder 64 and element 65 upper corners and lateral displacement in clearing relation with said feedway, and the lower end of said tool 68 is worked as a downwardly-directed, semi-circular recess above a wedge-shaped shoe cooperating with the feedway floor, so that, a stock wire section formed with an offset 49 being clamped between the shoulder 64 and element 65, travel of the tool 68 downwardly of its mounting in the block 63 acts through its end recess and shoe to form the section offset 49 into a closed loop eye on the section upper end and to bend the so-formed eye into elevated relation of its upper margin away from the feedway floor and into consequent angular relation with the hook shank. Automatic, synchronized actuation of the tool 68 by

means of the member 16 is effected through a lever 69 swingable in a plane parallel to the table 15 about a pivot perpendicular to and fixedly upstanding from said table adjacent the block 63 upper end, the end of said lever outwardly beyond said pivot operatively connecting with the tool 68 upper end and the portion of the lever inwardly of the pivot overhanging the member 16 between spaced posts 70 fixedly upstanding from said member in position to alternately engage against opposite sides of the lever as said member is reciprocated, the upper of the posts 70 functioning through the lever 69 to withdraw the tool 68 relative to the block 63 and out of obstructing relation with the feedway as the member 16 approaches its lower reciprocatory limit and the lower of said posts functioning to swing said lever for eye-forming actuation of the tool 68 as said member approaches the upper of its oscillatory limits.

Just below the block 63, complementary abutments 71 and 72 rise from fixed relation with the table 15 to define outer and inner sides, respectively, of the feedway continuation and to mount hook-shaping means in operative association with a stock wire section held between the shoulder 64 and element 65 of the assembly. The abutment 72 slidably accommodates a stem 73 between the feedway and member 16 for projection of its outer end at times across and above the feedway and the shank of a stock wire section therein, and said stem 73, yieldably spring-urged toward the member 16, is formed with a rounded inner end overlying the member 16 margin for slidable cooperation with the notched margin of a cam block 74 carried by said member. The block 74 and the marginal notch 75 thereof are so correlated with their associated elements as to permit seated registration of the stem 73 inner end within said notch 75, and consequent retraction of the stem outer end out of obstructing relation with the feedway, when the member 16 is at the lower limit of its reciprocation, and to hold said stem with its outer end intersecting said feedway during the rest of the actuating member cycle, and said stem outer end is formed as a head 76, marginally worked to conform with the inner outline of the desired hook bight, about which the stock wire section is bent and fitted to ultimate finished shape. In its operative position, the head 76 preferably end-closes against the face of the abutment 71 as a mandrel fully obstructing the upward passage between the adjacent abutment 71 and 72 faces and in position for cooperation with an arcuate shaping finger 77 actuatable to roll and form the hitherto straight lower portion of the stock wire section thereabout. The finger 77 is operatively housed within a slot in the table 15 intersecting the feedway below and downwardly of the table from the working position of the head 76, and is arranged for oscillation about a shiftable pivot 78 mounted in the table 15 below the floor and in a direction perpendicular to the length of the feedway, said pivot 78 being so associated with and mounted in said table as to have limited scope for displacement of its axis in a plane parallel to the table surface and in a direction parallel to the feedway. The free, working end of the finger 77 is adapted to move about the pivot 78 from full retraction within the table slot, where it closely underlies the feedway floor downward extension, through an upwardly-directed arc to coaction with the side of the head 76 remote from the block 63, and to lift and bend the stock

wire section free lower portion overlying said finger against and about said head as an incident of such motion, to which end the finger free tip is rounded and merged smoothly with a concavity in the finger upper margin contoured to coat with and clamp the stock wire section against the head 76 when said finger attains the limit of its work stroke. An extension of the finger 77 below the table 15 and beyond the pivot 78 is operatively linked, as at 79, to the lower end of a lever 80 hinged to the under side of the table 15 for oscillation in a vertical arc in substantially the same plane as the lever 26 and somewhat upwardly of the table 15 from said latter lever, the upper end of the lever 80 being operatively accommodated in a slot through the table 15 beneath the member 16 and engaging by means of a cylindrical terminal boss in and with the margins of an aperture 81 intersecting said member, so that actuation of said member is transmitted through the lever 80 and linkage 79 to rock the finger 77 about its pivot 78 for hook-shaping cooperation of the finger 77 and head 76 when said member is at the upper end of its range of travel and retraction of said finger below the surface plane of the table 15 when said member is at the lower of its travel limits, shifting of the pivot 78 relative to the table during such finger actuation imparting a sliding motion to the finger tip engaged against the stock wire and acting to roll said wire about the head 76 margin as a supplement to the clamping action had thereon.

If and when it is desired that the shank of the finished hook be barbed, roughened, or deformed, for the retention of artificial flies, lures, and the like, against sliding thereon, such modification of the shank is readily accomplished through means auxiliary to and operable in association with the hook shaping finger 77, for which purpose a slideway comprised of two obtusely-intersecting sections is formed in the table 15 with the shorter of its sections opening at an angle through the floor of the feedway at the lower margin of the block 63 and the longer of its sections diverging upwardly of and away from the table underside, and an angular, end-worked tool 82 is fitted within said slideway for disposition of its operating end just under the hook shank between the shoulder 64 and head 76 and for limited actuation longitudinally of the slideway longer section between clearing relation below the feedway floor and modifying engagement against the hook shank, the slideway shorter section being dimensioned to accommodate such limited displacement of the tool. A shoe 83 reciprocable longitudinally of the slideway longer section into and out of engagement against the adjacent end of the tool 82 is operatively connected by means of a link 84 with the finger 77 extension in such manner as to shift the work end of the tool 82 into modifying engagement with the hook shank when the finger 77 is moved into hook-forming cooperation with the head 76, and to release said tool for return to end-clearing relation with the feedway floor when said finger is retracted below the table surface; it being obvious that the work end of the tool 82 may be arranged to barb, notch, or offset the hook shank thereby engaged, in the specific form and style desired.

Constructed and arranged as illustrated and described, the improvement is continuously and automatically operable to convert stock wire material into fishhooks shaped to final form and complete save for tempering and possible surface

polishing or coating. As the member 16 is power-actuated, a straight feedway paralleling said member is fully opened and cleared of all obstruction to gravity-induced travel of stock material 5 sections therealong when said member is at the lower limit of its range of reciprocation, thus permitting said sections to progressively shift from one and to the next of the operating stations of the apparatus, and the operating elements of said stations are simultaneously manipulated with full effect on the material sections when said member is at the upper limit of its travel; certain element displacements incident to member travel intermediate said limits serving to condition the stations for the arrest and proper positioning therein of stock material received from a preceding station. Thus, the stock material emerging from the straightening stations is end-checked by the anvil 52 and plunger 53 and held for pointing, barbing, initial eye-forming, and severing operations all accomplished at the same stage of the member 16 cycle and in a single station, while at the same time the previously pointed, barbed, eye-worked, and separated section is checked between the shoulder 64 and element 65 of the next lower station where it is worked and shaped to complete and incline its eye, bend the hook, and modify its shank; the completely-formed section from said last station, 20 when released therefrom by retraction of the head 76 from within the hook bight, sliding down the table 15 surface for collection in a container, trough, or deposit on a traveling conveyor, as may suit the production arrangements of the installation.

As illustrated in Figures 1, 2 and 5, it is practical and efficient to associate two feedways with each member 16, one feedway being disposed on each side of said member and in operative association of its stations therewith, in which event the stations of the respective feedways may be spaced, located, and arranged for the production of hooks of the same, or of different sizes, as may be desired. Further, it is feasible to associate a plurality of members 16, each serving two feedways, in parallel and in operative relation with a single table 15 and, if desired, in powered relation with a single energizing unit, thereby economically adapting the improvement to a wide range of production size and quantity requirements.

Since many changes in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A fishhook-forming device comprising a table longitudinally inclined to the horizontal for the gravity-induced sliding of wire sections therealong, a straight, rigid, actuating member groove 65 seated in and for reciprocation longitudinally of the table upper face, means for the cyclic power reciprocation of said member, an abutment and a complementary shiftable shoe adjacent the table upper edge definitive of a straight feedway 70 on the table surface paralleling the member reciprocatory path, means operable to shift said shoe toward said abutment with straightening effect on a wire length therebetween at one limit of member reciprocation and to retract said shoe 75 away from said abutment for opening of the feed-

way at the other limit of member reciprocation, a forming die and a complementary shiftable forming element continuing said feedway below said abutment and shoe cooperable in reaction to member reciprocation to laterally offset a section of wire in said feedway and to sever such wire at the upper end of the offset, a channeled block overlying and continuing said feedway below said forming die and element, a plunger stop reciprocable in said block in reaction to member reciprocation to obstruct said feedway at times, to open said feedway at the limit of member reciprocation characterized by shoe and abutment and forming die and element separation, and to close with wire-pointing effect against an anvil in the feedway floor at the other limit of member reciprocation, wire-barbing means shiftable in said block in reaction to member reciprocation when said plunger stop is closed against its anvil, a second channeled block overlying and continuing said feedway in spaced relation below said first block, and means associated with said second block and reactive to member reciprocation operable to position and hold a feedway-accommodated wire section, to close the previously-formed lateral offset as an eye on one end of the section, and to roll the section other end into a hook bight.

2. The organization according to claim 1, wherein the shiftable shoe is carried on one end of a perpendicularly-related arm guided for reciprocation transversely of the table and spring-urged away from said abutment toward said member, the end of said arm remote from the shoe is rounded for sliding engagement with the member side margin to normally urge said shoe toward the complementary abutment, and the member side margin is formed with a cam notch for the accommodation of said arm rounded end when the member is at the lower limit of its reciprocation longitudinally of the table.

3. The organization according to claim 1, wherein said forming die and forming element are provided with complementary shoulders cooperable with shear effect on a wire therebetween when the forming element is closed against its die.

4. The organization according to claim 1, wherein said forming element is carried on the end of an arm guided for reciprocation transversely of the table and spring-urged away from the die toward said member, the end of the arm remote from the die is rounded for sliding engagement with the member side margin to normally urge the forming element toward its die, and the member side margin is formed with a cam notch for the accommodation of said arm rounded end when the member is at the lower limit of its reciprocation longitudinally of the table.

5. The organization according to claim 1, wherein said plunger stop is carried on one end of an arm hinged to oscillate in a plane perpendicular to the table surface and correspondingly reciprocates in its block mounting, and the other end of said arm overhangs the actuating member for coaction at times with the cammed face of a block fixed to and shiftable with said member.

6. The organization according to claim 1, wherein said plunger stop is formed with an eccentrically worked lower end cooperable at times with the complementary face of an opposed

anvil to point a wire section end engaged therebetween.

7. The organization according to claim 1, wherein said wire-barbing means is a chisel-type tool slidable in its block-mounting at an angle relative to the feedway floor and is hingably carried on one end of an arm mounted for oscillation in a plane paralleling the table surface, the other end of said arm overhangs the actuating member, and spaced elements upstanding from said member on opposite sides of said arm end apply member reciprocation to effect oscillation of the arm.

8. The organization according to claim 1, wherein the means for positioning and holding a feedway-accommodated wire section relative to said second block comprises a shoulder interrupting the block channel and partially obstructing the feedway for engagement by the previously-formed wire section lateral offset, a die element shiftable in said second block transversely of the table in opposition to said shoulder and normally spring-urged away from the latter, a rounded end on said die element remote from said shoulder disposed for sliding engagement against a side margin of the actuating member, and a cam notch in the member side margin for the accommodation of said element rounded end when the member is at the lower limit of its reciprocation longitudinally of the table.

9. The organization according to claim 1, wherein the means to close the previously-formed wire section lateral offset into an eye on the end of the wire section comprises a shoulder and complementary die element in said second block disposed to grip the wire section therebetween just below said offset, a forming tool shiftable laterally and longitudinally of said second block into eye-completing coaction with said shoulder and die element, a lever swingable parallel to the table surface in engagement with said forming tool at one end and overhanging the actuating member at its other end, and spaced elements upstanding from said member on opposite sides of said lever end for shift of the latter in reaction to member reciprocation.

10. The organization according to claim 1, wherein the means for rolling the wire section end remote from the lateral offset into a hook bight comprises a mandrel projectible as an incident of actuating member reciprocation transversely across and above the feedway adjacent the second block lower margin, a slot in the feedway floor below the mandrel position, a shaping finger accommodated within and to rise into co-operation with said mandrel through said slot, a pivot for said finger transversely of the feedway below the table and shiftable longitudinally of the feedway to impart a rolling action to the finger, and a linkage between said finger and actuating member operable to shift said pivot and simultaneously rock the finger upwardly through its slot in reaction to member reciprocation.
